UNITED STATES PATENT OFFICE.

NORRIS E. GOODRICH, OF BATTLE CREEK, MICHIGAN, ASSIGNOR TO SANITARIUM AND HOSPITAL EQUIPMENT COMPANY, OF BATTLE CREEK, MICHIGAN, A CORPORATION OF MICHIGAN.

THERAPEUTIC LAMP.

Application filed July 29, 1925. Serial No. 46,750.

This invention relates to improvements in therapeutic apparatus, and more particularly pertains to electric lamps extensively employed for therapeutic purposes in physicians' offices, hospitals, sanitariums, etc.

Electric lamps for therapeutic purposes are coming into extensive use for the treatment of various infections, diseases and ailments, and I have found that with the use 10 of a lamp of high wattage the curative effect of such devices may be greatly extended in range. There are, however, a number of attendant disadvantages to be met in attempting to adapt the usual therapeutic lamp to 15 a high-powered electric lamp. The greatest of these perhaps, is the confinement of the large amount of heat generated by the lamp within the reflector with the result that the reflector becomes highly heated causing the cement securing the lamp base to the lamp neck to soften and loosen, increasing the 20 liability to fire and physical injury.

Another disadvantage of an apparatus of this character when used with a high wattage electric lamp, is the difficulty of attaining the requisite proportion of heat and light rays. It is difficult, if not impossible, to obtain the correct proportions of heat and light rays by the ordinary means of adjusting the 25 apparatus toward or from the part to be treated. I have discovered that the several foregoing objections may be entirely overcome and to that end have devised the novel invention hereinafter described.

It is one object of my invention to provide 30 an easily adjustable reflector and one which may be readily adapted for use in connection with the therapeutic lamp stand described and claimed in my copending application,

40 Ser. No. 43,109, filed July 13, 1925.

Another object of the invention is to provide 45 a reflector mechanism adaptable for use in connection with a high powered electric lamp such as one of 1500 watts without the retention of the heat as in former reflecting mechanisms for this purpose and a reflector in which positive ventilation is provided for the inducement of thorough and rapid circulation of air.

50 A further object includes the provision of means whereby the current supplied to the lamp, and thus the effective light and heat ray projection, may be regulated and controlled.

Still further objects and advantages of my invention should be readily appreciated after reading the following description and claims in connection with the accompanying drawing in which:

Fig. 1 is a side elevation partly in section 60 of therapeutic apparatus embodying the above noted features of my invention.

Fig. 2 is a top plan view of the reflector and ventilating mechanism shown in Fig. 1.

Fig. 3 is a section taken on the line 3—3 of 65 Fig. 2 showing an electric lamp situated in the reflector, and,

Fig. 4 is a diagrammatic view showing a circuit embodying part of the invention.

In the drawing, 2 designates a base constituting a support for the lower end of a lamp standard 3 upon which a ventilated rheostat element 4 and a bracket clamp generally designated 5 connected with a balanced raising and lowering mechanism generally designated 6, may be mounted as more particularly described in the copending application to which reference has been made above. The bracket clamp 5 supports a lamp supporting trunnion yoke 7 which in turn engages trunnions 8 and 9, which are secured to the reflector 11 by rivets or in any other suitable manner, whereby the reflector may be swung in a vertical plane through an angle of approximately 90°. 85 The arms of the yoke 7 are adapted to be positioned over trunnion spindles 12 and 13 as will be apparent from Fig. 3 and are preferably slightly recessed as at 14 to provide annular chambers about the spindles 12 and 13 for the reception of light springs 15 cooperative with nuts 16 and washers 17 to frictionally retard movement of the reflector 11 in a vertical plane whereby the reflector may be positioned as desired.

High-powered electric lamps 18 are usually provided with long necks or stems 19 for the purpose of preventing heat generated by the filament thereof, from softening the cement by which the usual lamp base 21 is secured. However, when such lamps are placed in a closed reflector, the heat generated by the filament is conducted and conveyed toward the base with the result that the base cement often softens and allows the lamps to pull loose. It also often happens that an attendant or even the patient is burned severely upon contact with the highly heated

portions of the reflector or they might be seriously shocked should the electric wires short-circuit with the lamp. In order to overcome these disadvantages, I prefer to 5 provide the reflector with a series of ventilating openings 22 located through the reflector walls to the rear of the focus of the reflector and with one or more heat and light ray reflectors or baffles 23 secured about the 10 perimeter of a lamp receiving opening cut in the rear of the reflector. In the present instance, the baffle 23 is of conical shape and is provided with outwardly flared portions 24 whereby it may be secured to the perimeter 15 of the opening to the rear of the reflector and is truncated to provide an opening sufficiently large to receive and lie in contiguous relation to the electric lamp 18. The forward face of this baffle is preferably a reflecting surface and the back face thereof is 20 preferably covered with an insulating material such as asbestos.

Also secured to the perimeter of the opening to the rear of the reflector, is a cap 25 provided with any desirable number of ventilating openings 26, a lamp socket member 27 and a second conical baffle 28 similar in design, construction and function to the baffle 23. Both baffles 23 and 28 may be 30 adapted to aid in positioning the lamp 18 and its stem 19 within the reflector since they lie practically in contact relation to the bowl and neck thereof, and these baffles with their reflecting forward bases, successfully reflect 35 or deflect any light rays and heat currents directed upwardly toward the base 21 of the lamp, out through the ventilating openings 22 and 26, or direct the light rays outwardly to their proper and desired direction.

40 In operation, heat generated within the reflector proper, will rise and strike the baffles 23 and pass outwardly through the several openings 22 into the outer atmosphere and thus establish a positive circulation around the lamp and through the reflector. In a similar manner also, light rays and heated gas generated between the two baffles 23 and 28 will be directed outwardly away from the base of the lamp to the inside surface 45 of the cap 25 where the heated gases will be dissipated through the several ventilating openings 26. The cap 25, of course, may be made of any suitable heat insulating material or it may be made of metal since 50 the radiation therefrom is sufficient to dissipate any heat absorbed thereby.

The rheostat 4 may consist of a number of independent resistance elements 29 and 31 suitably insulated and connected between a 55 line 32 to a source of power and a line 33 connecting with a lamp socket in the usual manner. Any desirable switch mechanism 34 may be utilized for connecting the resistance elements in series with the lamp line singly or in multiple, or if desired, the resistance

may be entirely cut out as will be readily appreciated from Fig. 4. With this arrangement together with the adjustable stand mechanism, I am enabled to more perfectly adjust the lamp to the proper distance from the patient to obtain the proper relative amounts and proportions of heat and light ray projection. In other words, adjustment of the lamp to the various needs or demands is greatly simplified.

70 While I have herein shown and described for purposes of illustration one practical embodiment of the principle of the invention which, in practice, has been found to satisfactorily effectuate the stated purposes and 75 objects thereof, it should be understood that many of the structural details may be variously modified without departing from the spirit of the invention or sacrificing any of the advantages thereof. Hence, I do not 80 limit the invention to the particular embodiment shown, but reserve all such variations, 85 modifications and mechanical equivalents as fall within the spirit and purview of the appended claims.

90 I claim:

1. In a therapeutic lamp, a parabolic reflector, a ventilating cap having ventilation openings and a lamp socket therein behind the focus of the reflector, a plurality of ventilating openings in the reflector behind the focus thereof, and a plurality of heat and light ray deflectors adapted to deflect a portion of the heat and light rays falling behind the focus of the reflector, through said 100 ventilation openings.

2. In a therapeutic lamp, a parabolic reflector having oppositely disposed trunnions for swinging movement thereon, a lamp socket connected to said reflector to dispose 105 a lamp within said reflector, said reflector having ventilation openings therein, and means for reflecting light and deflecting heat rays away from said socket and towards said openings.

3. In a therapeutic lamp, a parabolic reflector, a ventilator cap member having ventilation opening therein and forming a lamp socket engaging means, a lamp socket in said means, and means with said cap for 115 deflecting heat away from said socket toward said openings.

4. In a therapeutic lamp, a reflector having ventilation openings therein, means for positioning and securing a source of light in front of the reflector, and means positioned between said reflector and said first named means for deflecting light and heat rays away from the first said means toward said 120 openings.

5. In a therapeutic lamp, a parabolic reflector, a ventilating cap having ventilating openings therein, secured to said reflector, and having a lamp socket therein on the longitudinal axis of said reflector, and a 125 130

light and heat ray deflector having an opening therein concentric with said socket secured to said reflector and projecting forwardly therein for intimate association with 5 a lamp in said socket.

6. In a therapeutic lamp, a parabolic reflector having a portion to the rear of its focus turned inwardly and formed with an opening therein whereby the neck of an electric lamp may be passed therethrough to dispose the bowl of the lamp within the reflector, said reflector having ventilation openings adjacent said inturned portion whereby heat generated by a lamp may be 10 dissipated without the reflector, said portion serving as a deflector of heat and light rays directed toward the base of a lamp.

7. In a therapeutic lamp, a parabolic reflector having a portion to the rear of its focus indented and provided with an electric lamp neck receiving opening, and an insulating covering for the rearward surface of said indented portion.

8. In a therapeutic lamp, a parabolic reflector having an inwardly projecting truncated cone baffle to the rear of the focus of the reflector, and a reflecting surface on the face of the baffle interior of the reflector.

9. In a therapeutic lamp, a parabolic reflector having an inwardly directed conical baffle, projecting through a wall thereof, said baffle being truncated to provide an electric lamp receiving opening therethrough, and a reflecting surface on the side of said baffle facing the interior surface of 35 said reflector.

10. In a therapeutic lamp, a parabolic reflector, an inwardly directed hollow conical baffle connected at its base to said reflector to the rear of the focus thereof, a reflecting 40 surface on one side of said baffle, and an insulation covering on the other side of said baffle.

11. In a therapeutic lamp, a parabolic reflector having a series of inwardly directed 45 conical baffles, said baffles being truncated to provide aligned openings for the reception of the base and neck of an electric lamp, and a reflecting surface on said baffles adapted to reflect light rays directed toward 50 the base of the lamp outwardly and away therefrom.

In witness of the foregoing I affix my signature.

NORRIS E. GOODRICH.
